UNITED STATES PATENT OFFICE.

JOHN R. REYNOLDS, OF HARTFORD, CONNECTICUT, ASSIGNOR TO THE SMYTH MANUFACTURING COMPANY, OF HARTFORD, CONNECTICUT, A CORPORATION OF CONNECTICUT.

BACK-SUPPORT FOR STITCHING-MACHINES.

1,246,158.

Specification of Letters Patent.

Patented Nov. 13, 1917.

Application filed October 6, 1916. Serial No. 124,098.

To all whom it may concern:

Be it known that I, JOHN R. REYNOLDS, a citizen of the United States, residing at Hartford, in the county of Hartford and 5 State of Connecticut, have invented a new and useful Improvement in Back-Supports for Book-Stitching Machines, of which the following is a specification.

Books are made of sections stitched together at the back or folded edges of the sheets, and the sections of different books vary in size according to the thickness of the paper and the length, width, and number of sheets of paper. In an automatic 10 book stitching machine as each section is stitched to those preceding the whole are pushed back to make place for the succeeding section, and in some machines a large number of sections are thus stitched together before they are separated and removed. As the sheets of paper are folded to form the sections there are always a greater or less number of folds at the head edge than at the tail edge, consequently the 15 sections will be thicker and tend to occupy more space at the head edge than at the tail edge. When a large number of sections are stitched together the amount of this difference becomes very material, and if provision is not made to control this it causes the sections to "fan out" at the head edge. The wider the sections and the thinner the paper the less strength they have to support themselves on edge after being stitched, 20 and if they are not properly supported they tend to "droop". If the head edges "fan out", or if the sheets "droop" the stitching is liable to be so pulled as to break the threads or to become loose and irregular 25 and thus spoil the book.

This invention relates to the mechanism which acts in conjunction with the stitching and feeding mechanism for supporting the sections on edge so that the other mechanisms will operate satisfactorily and leave the stitching in good condition.

The object of the invention is to provide a book support which will keep thick as well as thin sections square as they are fed back, 30 and will hold upright and prevent from sagging and drawing the stitching, sections of thin wide sheets of paper as well as sections of thick narrow sheets of paper, and yet will yield sufficiently to permit the 35 proper automatic feed of the sections as

they are stitched and pushed back during the operation of the machine.

In attaining this end the platform upon which the bottom edges of the sections rest and are pushed back, is provided with a 60 back support so constructed and arranged that with pressure correctly applied and of just the right amount, as when the sections are square and held upright, it will automatically feed backward as the sections are 65 stitched at the front, but will not feed backward unless the pressure is sufficient and properly applied to hold the sections square and upright, the resistance of the back support being readily adjustable according 70 to the conditions arising with books of various size, shape and stock.

Figure 1 of the accompanying drawings shows an elevation, with parts in section, of the section supporting and feeding mechanism of an automatic book stitching machine constructed according to this invention. Fig. 2 is a similar view showing the same parts in another position. Fig. 3 is a view looking toward the front showing the 80 knife blade that is used at the tail edge in this machine for assisting in supporting the sections. Fig. 4 shows a plan with parts in section of the section feeding and supporting mechanisms. Fig. 5 is a horizontal section taken through some of the book sections illustrating the manner in which the folds at the head edge thicken that edge and tend to "fan out" the sections. Fig. 6 is a larger plan of a portion 90 of the platform and the back support showing a number of signatures held properly, the dotted lines showing the way in which the signatures tend to work out of square if not properly supported. Fig. 7 shows a 95 vertical section taken through the back support on the plane indicated by the dotted line 7—7 on Fig. 6.

In the views only so much of an automatic book stitching machine of a well 100 known type is shown as is contiguous to and as co-operates with the improved means for supporting the sections which embody this invention. In this machine the folded book sections 1 are carried one at a time up to 105 stitching position by the vertically movable arms 2 on which the sections are hung by the operative. As the arms start up fingers 3 swing up to hold back the lower edges of the sections previously stitched and that 110

rest upon the platform 4. The fingers are fastened to a shaft 5 having a rocker arm 6 that by a link 7 is connected with the end of a lever 8 which is oscillated at the correct time by the vertical reciprocation of a cam actuated rod 9. The platform upon which the sections rest is carried by vertical screw rods 10 that are provided with crank handles 11 so that the rods may be turned and the height of the platform adjusted according to the width of the sections. The finger shaft and the connected parts are carried by the platform so the fingers will move up and down when the height of the platform is adjusted.

As the section carrying arm goes up the presser bar 12 moves forward to permit the arm and section to reach stitching position. The presser bar extends across the front of the machine and is attached to rack bars 13 movably supported by the frame. Engaging with the racks of these bars are pinion segments 14 fastened to a shaft 15 provided with a rocker arm 16 that is rocked at the correct time by the cam reciprocated rod 17.

When the section has reached its highest position it is stitched to the preceding section and the carrying arm descends. As the arm goes down the presser bar is drawn back and forces the stitched sections rearwardly. A bar 18 swings back as the arm moves down and the presser bar moves back so as to push back the front section near the middle. This bar immediately swings forward as the presser bar forces the section rearward and the carrying arm descends. When the carrying arm goes down the fingers swing forward so as to get out from back of the section just stitched. These operations are repeated in sequence as the sections are carried up and stitched, and the mechanisms for performing them are old and well known, consequently are not described in more detail.

As the stitched together sections stand with their lower edges resting upon the platform (Figs. 1, 2) they must be held closely pressed together or they will droop and slump down so as to strain the stitching if the threads do not break, and as the sections are thicker at the head edge than at the tail edge, owing to the folding of the sheets of which the sections are formed (Fig. 5) unless tightly pressed the sections will "fan out," that is, widen out at the head edge and tend to stand obliquely across the platform instead of squarely, as indicated by dotted lines in Fig. 6. The back support, however, cannot be immovable and form a rigid wall to enable the necessary pressure to be exerted for compacting the sections, for it must yield as the sections are stitched to afford room for the subsequent sections to be stitched.

To assist in retaining the tail edges of the sections, that is, the rough edges which are not folded and which form the bottom edge of the completed book, a knife blade 19 is secured to a block 20 that is adjustably fastened on the frame bar 21. This blade is adjusted so that it will cut slightly into the tail edges of the sections near the back folds (Figs. 2, 3, 4) and thus aid in supporting these edges of the sections. The head or folded edges of the sections are thicker; stiffer and smoother and consequently do not need to be thus supported.

In order that the sections may receive from the presser bar the required pressure to keep them square, notwithstanding that they are thicker at the head edge than at the tail edge, and to prevent them from drooping as a result of looseness, a back support is provided that can be moved rearward only when the required amount of pressure is applied squarely across its whole face. This support consists of a block 22 that has its underside fitted to an undercut guideway 23 which extends from front to back in the upper surface of the platform. This guideway is formed nearer the head side of the platform than the tail side so that the block will be nearer the side of greatest pressure. In sockets in vertical hubs 24 on the block are plungers 25 that are forced downward by springs 26, the tension of which is regulated by thumb screws 27 screwed into the ends of the hubs. The springs force the plungers down upon the rails 28 which form the guideway with a pressure determined by the adjustment of the screws. A vertical groove 29 is formed in the front of the block 22 for receiving the back plate 30 of desired size. The block is fitted to the guideway so that pressure upon one side of the back plate will not move it rearwardly, and the friction of the plungers is made of such resistance that only the required amount of pressure exerted squarely and uniformly across the back plate will move the block.

As a result of this construction the book sections can be crowded together by the pressure of the presser bar until the space between the presser bar and the back plate is completely filled. Unless the sections completely fill the space and push back squarely and uniformly across the whole face of the back plate, the back plate will not yield. This allows the application of such a degree of pressure that the folded head edges of the book sections will be crushed together and the tail edges compactly held so that the sections will be supported firmly and squarely, and thus enable the other mechanisms of the machine to properly perform their functions and the stitching to be of the desired regularity and uniformity.

The invention claimed is;

1. The combination in a book stitching machine, of a platform for supporting on edge the stitched book sections, a guideway 5 extending on said platform from front to back near the head side, a slide with a portion loosely fitted to and movable back and forth along said guideway, a back plate carried by the slide, and adjustable means 10 carried by the slide and engaging opposite sides of the guideway for frictionally resisting the movement of said slide and back plate along the guideway.
  2. The combination in a book stitching machine, of a platform for supporting on edge the stitched book sections, a guideway extending from front to back on said platform, a slide with a portion loosely fitted to and movable back and forth along said 20 guideway, spring plungers carried by the slide and engaging opposite sides of the guideway for limiting the freedom of movement of said slide, and a back plate carried by the slide.
  3. The combination in a book stitching machine, of a platform for supporting on edge the stitched book sections, a guideway extending from front to back on said platform, a slide with a portion loosely fitted 30 to and movable back and forth along said guideway, spring plungers carried by the slide and engaging opposite sides of the guideway for limiting the freedom of movement of said slide, and a back plate removably mounted on the slide.
  4. The combination in a book stitching machine, of a platform for supporting on edge the stitched book sections, a guideway extending from front to back on said platform, a slide with a portion loosely fitted to and movable back and forth along said 40 guideway, spring plungers carried by the
- slide and engaging opposite sides of the guideway for limiting the freedom of movement of said slide along the guideway, 45 and means for adjusting the action of the plungers on the guideway.
5. The combination in a book stitching machine, of a platform for supporting on edge the stitched book sections, a knife 50 blade for engaging the tail edges of the sections and assisting in supporting the same, mechanism for pushing the upper edges of the sections rearward and along the knife blade, mechanism for pushing the lower 55 edges of the sections rearward on the platform, a slide loosely fitted to and movable back and forth along a guideway on the platform for resisting the rearward movement of the sections, a back plate carried by 60 the slide, and mechanism for adjusting the amount of resistance of said slide to the rearward movement of the sections on the platform.
6. The combination in a book stitching 65 machine, of a platform for supporting on edge the stitched book sections, a guideway extending on said platform from front to back nearer one edge than the other, a knife 70 blade for engaging the tail edges of the sections and assisting in supporting the same, mechanism for pushing the upper edges of the sections rearward and along the knife blade, mechanism for pushing the lower 75 edges of the sections rearward on the platform, a slide loosely fitted to and movable back and forth along said guideway for resisting the rearward movement of the sections, a back plate carried by the slide, and mechanism for adjusting the amount of resistance of said slide to the rearward movement of the sections on the platform.
